SOIL TESTING APPARATUS

John W. Black, Crittenden County, Ark.

Application April 29, 1947, Serial No. 744,613

8 Claims. (Cl. 73—12)

(Granted under the act of March 3, 1883, as
amended April 30, 1928; 370 O. G. 757)

1

The invention described herein may be manufactured and used by or for the Government for governmental purposes, without payment to me of any royalty thereon.

The present invention relates to a testing apparatus designed especially for the testing of compaction of soils, wherein a gravity-actuated tamping member acts on a given sample of soil to compact the same.

The apparatus of the present invention is characterized by simplicity of construction and operation and it has for one of its objects the provision of means whereby a controlled but constant tamping force is imparted to the specimen being tested.

A further object of the invention is the provision of an improved tamping device wherein the device is constantly guided in its movements so that it will impact upon the sample at right angles thereto without any preliminary adjustment or manipulation of the tamping member being required.

A still further object of the present invention is the provision of improved mechanism for predeterminedly releasing the tamping member.

A still further object of the invention is to provide a means for predeterminedly controlling the impact force of the tamping means.

A still further object of the invention is the provision of an improved construction for rotating the sample being tested to assure uniform application of compacting force thereon.

Further objects and advantages of the present construction will become apparent as the description proceeds, and the features of novelty will be pointed out in particularity in the appended claims.

The present invention will be understood more readily from a consideration of the accompanying drawings, in which:

Fig. 1 is a perspective view of the improved apparatus;

Fig. 2 is a fragmentary sectional elevation of the apparatus;

Fig. 3 is an enlarged view of the upper portion of the apparatus shown in Fig. 2, the view showing in greater detail the construction and operation of the improved clutch mechanism forming a part of the present invention;

Fig. 4 is a sectional plan view taken on the line IV—IV of Fig. 2 showing further details of the clutch mechanism included in the present invention;

Fig. 5 is a view similar to Fig. 4, but with parts omitted;

Fig. 6 is a side elevation of the clutch element shown in Fig. 5;

Fig. 7 is a plan view of friction clutch elements included in the clutch member of Figs. 4 and 5;

Fig. 8 is a side elevation of the clutch elements of Fig. 7;

Fig. 9 is a plan view of the base element of the apparatus shown in Fig. 1;

Fig. 10 is a sectional elevation taken on the line X—X of Fig. 2;

Fig. 11 is a plan view of the turntable for receiving the specimen-holder shown in Figs. 1 and 2;

Fig. 12 is a plan view of the turntable support shown in Figs. 1 and 2.

Referring more particularly to the drawings, the improved apparatus of the present invention comprises a frame A which comprises a base 14 to which is mounted a rear channel member 16, this channel member being mounted vertically to the base 14 and rigidly supported by angle bracket 18. The base 14 is an inverted channel member, resting on flanges 20, the bracket 18 being secured to the base 14 and to the vertical channel member by bolts, or the like, 22.

The frame A also includes a cylindrical bar 24, which is threaded into the base 14 and held by cooperating nuts 26, 26a. This bar 24 receives an adjustable stop 28 and an actuating handle 29 for the tamping mechanism, all of which will be described hereinafter. The channel member 16 and the bar 24 are maintained in vertical spaced relation by a top plate 30, which is provided with suitable holes therethrough, which will be referred to hereinafter, for the passage of certain actuating instrumentalities which also will be described hereinafter. Certain of these holes in the top plate 30 are adapted to receive bolts or equivalent fastening means 32 that secure the top plate 30 to one arm of an angle bracket 34, the other arm of which is secured by bolts or other securing instrumentalities 36 to the channel 16, the plate 30 being supported by this angle bracket and also by a nut 38 threadedly mounted on the cylindrical bar 24, the end of which extends through the top plate 30 in a suitable hole 40 provided therefor in the top plate 30, and secured by a top nut 38a.

Also secured to the rear frame channel 16 is an angle bracket 42, the arm 44 of which supports a plate 46 that is secured to the bracket arm 44 by bolts 48. The bracket 42 is secured to

the channel 16 by bolts or equivalent fastening means 50. The plate 46 extends horizontally from the vertical channel 16 and is provided with a hole 52 for reception of a cylindrical rod 54 that is held vertically in the plate 46 by a nut 56 threadedly secured to the rod 54 on the underside of plate 46 for locking the rod 54 in position. The rod 54 extends through a hole 58 provided therefor in top plate 30 and is secured in place by a nut 60 threaded on the upper end of the rod 54. The plate 46 is provided with a relatively large opening 62 through which passes an actuating bar 64 of the tamping mechanism, which bar also passes through a hole 66 in the top plate 30 provided therefor, the bar 64 extending through this hole for a suitable distance so that it will still project therethrough when the tamping head 68 on the lower end of the bar 64 is in lowermost position. The plate 46 and top plate 30 therefor act as guides for the tamping bar 64 during operation of the bar and maintain the bar 64 continuously in vertical position.

The tamping bar 64 and the tamping head 68 on the lower end thereof are adapted to be raised a predetermined adjustable distance, and released for dropping, by gravity, on a sample of soil which is being tested contained in a suitable container 70 mounted on a turntable 72 held on a turntable support 74 that is mounted on the base 14 of the mechanism.

The lifting mechanism for the tamping bar 64 now may be described.

This lifting mechanism includes a clutch member 76, which has a generally rectangular body 78 that tapers uniformly, as indicated at 80, into an arm portion 82, a stop or abutment member 82a being affixed suitably to this arm 82 adjacent to its outer extremity. The end of the clutch body 78 opposite to the arm portion 82 is slotted, as indicated at 84, this slot fitting over the rod 54 for guiding the clutch member in vertical movement thereof while preventing horizontal turning movement of the clutch member. The clutch member 76 is a plate-like member, and the body portion 78 has a rectangular cut-out portion 86, the ends of which are provided with projecting retaining cams 88 which pivotally receive clamping jaws 92 by means of slot 90 in said jaws 92. These jaws 92 are recessed complementarily as is indicated at 93 for receiving the tamping bar 64.

The arm portion 82 and the rectangular body portion 78 with its cut-out portion 86 are proportioned so that the center of gravity of the entire clutch plate 76 passes through the plane of the intersection of the body portion 78 and the tapering portion 80, the clutch plate balancing along the line of this intersection.

The mid-portion of the tapering portion 80 is provided with a hole 94, in which is secured an operating cable 96. This cable passes through a hole 98 in the top plate 30 of the machine, the cable passing over a pulley sheave 100 that is mounted in a bracket 102 on shaft 104 rotating in bearings 106 in the bracket. The bracket 102 has both arms secured to opposite sides of a plate 108 held by screws 110 on the top plate 30. After passing over the sheave 100, the cable 96 passes through a hole 112 in top plate 30 that corresponds to hole 98, and is secured to a projecting lug 114 of the handle member 29 that is slidably mounted on the cylindrical frame bar 24, the cable 96 clearing the end of the arm portion 82 of the clutch plate. The position of the handle member 29 is determined by the position of the adjustable stop 28.

The complementary clamping jaws 92 have a slight opposite cam movement on the retaining cams 88 when the tamping bar 64 is received in the recesses 93, one of the clamping jaws 92 moving downwardly against the tamping bar 64 and the other of the clamping jaws 92 moving upwardly against the bar 64. This clamping action, acting responsively to the weight of the tamping bar 64 tilting the clutch plate 76 as indicated in Fig. 2, and clamping the tamping bar firmly between the clamping jaws 92. The tamping bar 64, together with its tamping head 68, is raised by moving the handle 29 downwardly along the vertical cylindrical frame bar 24, the lifting movement being effected through cable 96. The clamping jaws 92 automatically shift into clamping position on the tamping bar 64, coincidently with the start of the lifting movement, and remain in clamping position on the clamping bar until released at the end of the lifting stroke.

During this lifting stroke or movement, the clutch plate 76 is tilted approximately as indicated in dotted lines in Fig. 3, the clamping jaws 92 assuming their dotted line position indicated in this view immediately following the start of the lifting stroke. At the end of the lifting stroke, stop or abutment member 82a first engages the underside of the top frame plate 30, this tending to level the clutch plate to the approximate full line position of Fig. 3, while, subsequently to such engagement but almost coincidently therewith, the slotted end of the clutch plate engages abutment 116, this being a resilient abutment or stop member that is mounted suitably on the underside of the frame plate 30 and encircles the rod 54. This rod 54 guides the vertical movement of the clutch plate and prevents any rotary movement of the clutch plate and the tamping bar 64. The engagement of the abutment member 82a with the top plate 30 and the engagement of the slotted end of the clutch plate with resilient abutment 116 tend to level the clutch plate into the full line position indicated in Fig. 3. This leveling of the clutch plate automatically releases the clamping jaws 92 and causes the tamping bar and head to drop an impact upon a sample of soil in container 70, the amount of compaction effected being determined by the length of the downward stroke of the tamping device. The extent of this downward stroke is determined by the position of the stop 28 on the frame bar 24, since the handle 29 is pulled downwardly to raise the clutch plate 76 and the tamping bar 64, the position of the stop 28 measuring the distance of the drop of the clutch plate for its following grip on the tamping bar 64 for the next lifting of the tamping bar and tamping head. It is apparent that the balance of the clutch plate 76 is such that it will drop freely along the tamping rod until the resulting upward movement of handle 29 brings the handle into engagement with the stop and the weight of the clutch member transmitted through the cable 96 to stopped handle 29 puts the cable under tension. This tension will tilt the clutch member into clamping position on the bar 64 automatically responsively to the handle 29 reaching the stop 28. The adjustment of the stop 28 is effected by releasing a clamping pin 117 and then moving the stop 28 along the bar 24 to desired position.

As will be apparent, there will be adequate play between the rod 54 and the sides of the groove 84 in the clutch plate 76 to allow the requisite amount of tilting and leveling of the

clutch plate to effect the clamping and release of the tamping bar 64. Also, it will be observed from Fig. 5 that the clamping jaws 92 are removable for interchange with other similar jaws on the retaining cams 88 when replacement is desired.

In order to assure uniform compaction of a specimen of soil throughout its extent, the container 70, which receives the specimen, is adapted to be mounted on a turntable 72 rotation of which brings successive portions of the soil specimen under the tamping head 68.

The turntable 72 is provided with an upstanding central pin 118 which enters a corresponding recess 120 in the bottom 122 of the specimen container 70, a further pin 124 fitting into a complementary recess 126 in the bottom of the specimen container serving to key the container 70 to the turntable 72.

Turntable 72 is mounted on a turntable support 74 that is mounted on the base 14 of the instrument by screws 128, these screws passing through slots 130 in the base 14, and entering a retaining bar 132 beneath the base 14. The turntable support 74 has a central hole 134 therethrough, which is adapted to receive a cylindrical boss 136 extending from the lower surface of the turntable. The base 14 also has a similar hole 138 for the reception of this boss. The slots 130 permit lateral adjustment of the turntable assembly and specimen container relative to the tamping head 68. The base 14 is provided with a reinforcement 140 beneath the turntable assembly, as shown, and anchoring screws 142 anchor the testing mechanism to a foundation 144.

In Fig. 9, reference numeral 146 indicates the hole in the base 14 in which the vertical bar 24 of the frame is received, and reference numeral 148 represents the holes provided in the base 14 for reception of the locking screws 142.

Having thus described my invention, what I claim as new and wish to secure by Letters Patent is:

1. Testing apparatus comprising, in combination, a base, spaced frame members vertically mounted on the base, one of the frame members being a rear frame member and another of the frame members being a forward frame member, a top connecting plate rigidly interconnecting the frame members, a bracket horizontally extending from the rear frame member and rigidly mounted thereon, a tamping bar extending through the bracket and top plate and guided thereby during vertical movement of the tamping bar, a tamping head on the bar, manually actuated operating means for the tamping bar slidably mounted on the forward frame member, clutch mechanism connected with the operating means comprising a clutch plate including cam-acting clamping jaws for raising the tamping bar responsive to manual downward movement of the operative means along the forward frame member, an abutment means engageable by the clutch mechanism at the end of the upward travel thereof for automatically releasing the clamping means of the clutch mechanism from clutching engagement with the bar responsive to a predetermined vertical lifting movement of the tamping bar for allowing the said tamping bar to drop on a sample to be tested.

2. Testing apparatus comprising, in combination, a frame including a base, a pair of oppositely spaced frame members vertically mounted on the base and rigidly secured to the base, one

of the said frame members presenting a vertical plate-like surface towards the oppositely-spaced frame member, the said oppositely-spaced frame member being a bar, a top connecting plate for the frame members rigidly vertically interconnecting the frame members at the tops thereof and maintaining the frame members rigidly and uniformly spaced throughout their length, a bracket rigidly secured to the vertical plate-like frame surface, the bracket including a horizontally disposed plate, a tamping bar extending through the horizontally disposed plate and through the top connecting plate, a clutch including a tiltable clutch plate including gripping means for holding the tamping bar for lifting the said bar from a low to a high position, actuating means for the clutch slidably mounted on the bar of the frame, means connecting the clutch with the actuating means, whereby downward movement of the actuating means engages the clutch with the tamping bar, and abutment means on the top plate for moving the clutch plate from tilting gripping position for the bar to an approximately level bar-releasing position for releasably actuating the clutch responsively to engagement of the clutch with the abutment means, thereby automatically releasing the clutch from the tamping bar and causing the tamping bar to drop on a specimen to be tamped.

3. Testing apparatus comprising, in combination, a frame including a base, a pair of oppositely-spaced frame members vertically mounted on the base and rigidly secured to the base, one of the said members presenting a vertical, flat surface towards the oppositely spaced frame member, the said oppositely-spaced frame member being a bar, a top connecting plate for the frame members rigidly interconnecting the frame members at the tops thereof and maintaining the frame members rigidly and uniformly spaced throughout their length, a bracket rigidly secured to the vertical flat frame surface, the said bracket including a horizontally disposed plate, tamping means including a tamping bar extending through the horizontally disposed plate and the top plate, and a tamping head on the tamping bar, clutch means including a clutch plate and frictionally operable clutch jags mounted in the plate, an operating handle slidably mounted on the frame bar, an operating cable attached to one end of the clutch plate and to the operating handle, a pulley sheave for the cable mounted on the top plate, the said clutch jaws continuously embracing the tamping bar, said operating handle being movable downwardly thereby lifting the clutch plate for tilting plate until the clutch jaws come into operative engagement with the tamping bar for lifting the tamping bar, and abutment means on the top plate of the frame adapted to be engaged by the clutch plate for shifting the clutch plate and jaws from tilted position to a substantially level position for automatically releasing the clutch jaws from operative engagement with the tamping bar responsively to the end of the lifting movement of the clutch plate and tamping bar, thereby causing the tamping means to drop upon a specimen being tested.

4. Testing apparatus comprising, in combination, a frame including a base, a pair of oppositely spaced frame members vertically mounted on the base and rigidly secured to the base, one of the said members presenting a vertical flat surface towards the oppositely spaced frame member, the said oppositely spaced frame member

being a bar, a top connecting plate for the frame members rigidly interconnecting the frame members at the tops thereof and maintaining the frame members rigidly and uniformly spaced throughout their length, an angle bracket rigidly secured to the vertical flat frame, the said bracket including a horizontally disposed plate, tamping means including a tamping bar extending through the horizontally disposed plate and the top plate of the frame together with a tamping head on the tamping bar, clutch means including a clutch holder and frictionally operable clutch members in the holder, an operating handle slidably mounted on the frame bar, an operating cable attached to the clutch means and to the operating handle, a guide sheave for the cable mounted on the top plate, the said clutch members continuously embracing the tamping bar, said operating handle being movable downwardly into operative engagement with the clutch members and tamping bar for lifting the tamping bar, means on the top plate of the frame for automatically releasing the clutch members from operative engagement with the tamping bar responsive to lifting movement of the clutch means and tamping bar until the clutch means engage the clutch releasing means, thereby causing the tamping means to drop upon a specimen being tested, and adjustable stop means on the frame bar for limiting upward movement of the handle responsive to release of a downwardly-acting force on the handle thereby predeterminately adjusting the length of lift of the tamping means for predeterminately varying the amount of tamping force imparted to a specimen by drop of the tamping means.

5. Testing apparatus comprising, in combination, a frame including a base, a pair of oppositely spaced frame members vertically mounted on the base and rigidly secured to the base, one of the said members presenting a vertical flat surface towards the oppositely spaced frame member, the said oppositely spaced frame member being a bar, a top connecting plate for the frame members rigidly interconnecting the frame members at the tops thereof and maintaining the frame members rigidly and uniformly spaced throughout their lengths, an angle bracket rigidly secured to the vertical flat frame member, the said bracket including a horizontally disposed plate and the top plate together with a tamping head on the tamping bar, clutch means for actuating the tamping means, the clutch means including a substantially rectangular body portion, clutch jaws carried in the body portion, a relatively narrow projecting arm portion extending from the body portion, a tapering portion connecting the rectangular body portion and the projecting arm portion, the rectangular body portion, the tapering portion and the projecting arm portion being proportioned so that the clutch means will balance substantially along the line of intersection of the tapering portion and the rectangular body portion, the clutch jaws in the body portion embracing the tamping bar, actuating means for the clutch means slidably mounted on the bar of the frame, an operating cable connected to the clutch means at substantially the mid-point of the tapering portion, the said cable being also connected to the clutch actuating means, whereby tension on the operating cable causes the clutch means to tilt for operatively engaging the clutch jaws with the tamping bar for raising the tamping bar responsive to downward movement of the actuating means, and a

trip means adapted to be engaged by the clutch instrumentalities for leveling the clutch instrumentalities, thereby releasing the clutch means from operative engagement with the tamping bar.

6. Testing apparatus comprising, in combination, a substantially vertical frame comprising spaced upright members and a spacer frame member connecting the upright members and maintaining the said upright members in parallel spaced relation, testing means including a tamping bar and a tamping head on the bar mounted in the frame and retained and guided thereby, the said testing means being reciprocable through a predetermined cycle, a clutch plate, complemental cam-acting clamping jaws mounted in the clutch plate and adapted to grip the tamping bar responsive to a tilt of the clutch plate for effecting a stroke of movement of the tamping bar, and an abutment member on the clutch plate adapted to engage the said frame spacer member upon completion of the said stroke for leveling the clutch plate and jaws for causing the clamping jaws to release the said testing means.

7. Testing apparatus comprising, in combination, a substantially vertical frame comprising spaced upright members and a spacer frame member connecting the upright members and maintaining the said upright members in parallel spaced relation, testing means mounted in the frame and retained and guided thereby, the said testing means being reciprocable through a predetermined cycle, and including a vertically extending impact bar and a tamping head on the bar, a clutch plate including complemental cam-acting clamping jaws adapted to grip the said bar responsive to a predetermined angular tilt imparted to the clutch plate relative to the said bar, means for vertically lifting the said bar while gripped by the clamping jaws through a predetermined stroke of movement of the said bar, an abutment member on the clutch plate adapted to engage the frame spacer member upon completion of the stroke for imparting a leveling movement to the clutch plate thereby releasing the clamping jaws from the said bar for causing the bar to drop and to impact against a specimen being tested, and means for rotating the specimen for obtaining a uniform impaction thereof throughout its extent.

8. Testing apparatus comprising, in combination, a substantially vertical frame comprising spaced upright members and a spacer frame member connecting the upright members and maintaining the said upright members in parallel spaced relation, testing means mounted in the frame and retained and guided thereby, the said testing means being reciprocable through a predetermined cycle, and including a bar and a tamping head on the bar, a clutch plate including complemental cam-acting clamping jaws adapted to grip the said bar responsive to a predetermined angular tilt imparted to the clutch plate relative to the said bar, means for lifting the said bar while gripped by the clamping jaws through a predetermined stroke of movement of the said bar, an abutment member on the clutch plate adapted to engage the frame spacer member upon completion of the stroke for imparting a leveling movement to the clutch plate thereby releasing the clamping jaws from the said bar, resilient buffer means mounted on the frame spacer member adapted to be engaged by the clutch plate subsequently to engagement of the abutment member on the clutch plate and the

frame spacer member, and means for guiding the clutch plate during movement thereof while preventing lateral rotary movement thereof.
